UNITED STATES PATENT OFFICE.

HARRY E. HEATH, OF LYNN, MASSACHUSETTS, ASSIGNOR TO GENERAL ELECTRIC COMPANY,
A CORPORATION OF NEW YORK.

RESISTANCE UNIT.

No. 918,547.

Specification of Letters Patent.

Patented April 20, 1909.

Application filed May 7, 1907. Serial No. 372,325.

To all whom it may concern:

Be it known that I, HARRY E. HEATH, a citizen of the United States, residing at Lynn, county of Essex, State of Massachusetts, have invented certain new and useful Improvements in Resistance Units, of which the following is a specification.

This invention relates to resistance units for electric circuits and has for its object the provision of a device of this character which is simple and cheap to construct and combines lightness and strength with a high degree of efficiency and durability.

One of the objects of my invention is to provide a resistance unit which shall have as large a surface and as small an amount of material as possible.

In carrying out my invention I make the resistance unit in the form of a tube formed of strips of material wound into a close spiral. This may be done in various ways, two forms being shown and described in the accompanying specification.

In the drawings in which I have illustrated my invention, Figure 1 is an elevation partly in section of one form of my invention; and Fig. 2 is a similar view of another form without the connecting terminals.

In the construction of my resistance unit I take a strip 10 of resistance conducting material, such as sheet iron or the like, and wind it into a spiral with insulating material between the overlapping turns. The insulating material is preferably of flexible and refractory material, such as asbestos. In the form shown in Fig. 1, the asbestos and the metal are in strips of substantially equal width. The metal is first bent to the form shown in the drawing in any desired manner, as for instance by passing it through a die. The insulating material here described being flexible will conform to the shape of the metallic strip without any previous treatment. The two strips are arranged so as to overlap each other and are then wound into a closed spiral so that the metal turns will overlap each other with the asbestos strip 11 between them. The strips may be of any desired width so that the strip may overlap itself any number of times, and in this way the strips form a corrugated flexible tube, in which the turns are locked together by the bends in the strips. The tube is then provided with connecting terminals 12 and 13,

and a rod 14 is passed through the tube and terminals provided with nuts 15 for securing the whole in place. The tube may then be mounted between the brackets 16, if desired.

In the form shown in Fig. 2, the flat resistance conducting strip 17 and the asbestos strip 18 are wound in the form of a closed spiral as shown. In this form the corrugations are applied after the tube is formed. These corrugations may be circumferential and may thus be applied in a very simple manner. The corrugations in this case as well as in the form shown in Fig. 1 not only lock the spiral turns together but also lend strength to the tubes as a whole.

It will be understood, of course, that various modifications, both as to the material and the method of construction, may be resorted to without departing from the spirit of my invention, the scope of which is set forth in the annexed claims.

What I claim as new and desire to secure by Letters Patent of the United States, is,—

1. A resistance tube comprising similarly shaped strips of asbestos and conducting material spirally wound so as to overlap each other.

2. A resistance tube comprising a resistance conducting strip wound into a closed spiral having a strip of asbestos of substantially the same width between the overlapping turns.

3. A resistance tube comprising overlapping strips of insulating and conducting material wound into a closed spiral, the adjacent edges of said spiral being interlocked.

4. A resistance tube comprising overlapping strips of insulating and conducting material wound into a closed spiral, the adjacent edges of said spiral being locked together by corrugations.

5. A flexible resistance tube comprising a resistance conducting strip wound into a closed spiral, and a strip of asbestos wound between the overlapping turns, the said tube being provided with corrugations for locking the turns together.

In witness whereof, I have hereunto set my hand this third day of May, 1907.

HARRY E. HEATH.
